CLAIM

The ornamental design for a screen for a mobile terminal device with a graphical user interface, as shown and described.

DESCRIPTION

The file of this patent contains a least one drawing/photograph executed in color. Copies of this patent with color drawings/photographs will be provided by the United States Patent and Trademark Office upon request and payment of the necessary fee.

FIG. 1 is a front, top, and right side perspective view of a screen for a mobile terminal device with a graphical user interface showing our new design;

FIG. 2 is a front view thereof;

FIG. 3 is a reference view of FIG. 2;

FIG. 4 is a rear view thereof;

FIG. 5 is a top view thereof;

FIG. 6 is a bottom view thereof;

FIG. 7 is a right side view thereof;

FIG. 8 is a left side view thereof; and,

FIG. 9 is an enlarged detail view of the area 9 circumscribed on FIG. 3 of the screen for a mobile terminal device with a graphical user interface.

The broken line showing of elements of a graphical user interface including text and symbols is included for the purpose of illustrating portions of the article and forms no part of the claimed design. The broken line showing of a mobile terminal device is included for the purpose of illustrating environmental structure and forms no part of the claimed design.
